UNITED STATES PATENT OFFICE.

ROBERT SCHEANBLUM AND GRACE SCHEANBLUM, OF DANBURY, CONNECTICUT.

HAIR FOUNDATION.

1,365,548.

Specification of Letters Patent. Patented Jan. 11, 1921.

Application filed March 12, 1920. Serial No. 365,194.

To all whom it may concern:

Be it known that we, ROBERT SCHEANBLUM and GRACE SCHEANBLUM, citizens of the United States of America, residing at 5 Danbury, in the county of Fairfield and State of Connecticut, have invented certain new and useful Improvements in Hair Foundations, of which the following is a specification.

10 The invention relates to improvements in hair foundations, adapted for producing a roll effect.

It is an object of the invention to provide a foundation by which an attractive roll 15 may be given the hair to produce a puff effect, which is composed of relatively light material and fashioned to enable a free circulation of air beneath the hair.

It is a further object of the invention to 20 provide a foundation having hair supporting members adapted to receive the strands of hair therebetween and serve to bind or tie the hair within the foundation when the same is rolled to form a puff.

25 With the foregoing conception in mind, the invention primarily comprises a support or foundation having a pair of spaced curved supports extending above the base of the foundation and possessing inherent 30 resiliency, receiving therebetween a roll of hair, and serving to exert a slight pressure thereon to assist in holding the hair within the foundation against slipping when the hair is rolled thereon to produce the puff 35 effect.

In the accompanying drawings, we have disclosed a single embodiment of the invention, but it will be understood that the same is susceptible to many changes without 40 departing from the spirit of the invention.

In the drawings, Figure 1 represents a view of the device as being applied to the hair of the user; and Figs. 2, 3 and 4 are detail views.

45 Referring now more particularly to the drawings, the numeral 1 designates the base of the support which is disclosed as being of a substantially rectangular formation, and composed of relatively light wire which 50 is preferably wrapped with a fabric.

The base is provided with a continuation 2 forming a transverse support 3 which is bowed and extends well above the base entirely thereacross, being connected to the opposite side thereof by twisting the ends of

the material as indicated by the reference character 5. At the point 2 the wire of the base extends through a loop in the twisted portion 5 and then outwardly at right angles to form the support 3 which also serves to 60 connect the material forming the base.

Extending parallel with the support 3 is a second support 4, which is bowed in the same manner as the support 3 and is connected to the sides of the base by the twisting of the material thereof as indicated by the reference character 6. The two supports 3 and 4 are composed of a resilient material being spaced throughout their length to form an opening receiving therebetween the 70 strands of hair as shown in Fig. 4 of the drawings. The coil of hair 7 in this figure is first passed between one side of the base 1 and up over the curved support 4, thence downwardly into the space between the support 4 and the support 3 and finally around the opposite side of the base and over the top of the entire support. When thus passed through the different strands of the base, the hair is securely clamped or held by the 80 wire elements thereof, and the entire support is then rolled to distribute the hair thereover and produce a puff effect. 75

The hair when thus distributed over the base gives the appearance of an abundance 85 of hair, without resorting to switches and the like, and when the foundation is finally rolled and placed in position the hair will be firmly held between the wire strands thereof to prevent a slipping of the same. 90

In Fig. 2 we have disclosed a slightly different way of securing the hair to the form. In this disclosure the hair 7 passes under one side of the base, over both of the supports 3 and 4, and then down under the other side 95 of the base to be later returned as shown in Fig. 4. Here the resiliency of the different elements of the base serves to grip or hold the hair, and the support may be rolled without the liability of the hair becoming 100 disengaged therefrom.

Having thus described the invention, what we claim is:

1. A hair support of the character described comprising a relatively flat base, and 105 a plurality of curved supporting elements connected with the ends of the base and extending thereacross, said supporting elements being parallel throughout their length and spaced from the sides of the base. 110

2. A hair foundation comprising a base having side and end portions, and hair supporting elements consisting of spaced parallel members connected with the end portions of the base and being disconnected from the side portions thereof throughout their length.
3. A hair foundation of the character described comprising a base of metallic material having sides and end portions, of a plu-

rality of spaced metallic supports connected with the ends of the base and of a curved formation, said supports being spaced from each other and disconnected from the sides of the base throughout their length.

15 In testimony whereof we affix our signatures.

ROBERT SCHEANBLUM.
GRACE SCHEANBLUM.
